COMBINED INDICATING FUSE POST AND PILOT LIGHT

Edward V. Sundt, Wilmette, Ill., assignor to Sundt Engineering Company, Des Plaines, Ill., a corporation of Illinois

Application June 14, 1954, Serial No. 436,367

14 Claims. (Cl. 340—250)

The principal object of this invention is to provide a combined indicating fuse post and pilot light wherein a cartridge fuse protects the electric circuit to be protected, wherein a pilot lamp continuously indicates the condition of the cartridge fuse, the lamp being brightly illuminated when electrical power is being supplied to the circuit being protected by the cartridge fuse and being dimly illuminated when the cartridge fuse is blown, wherein the lamp and cartridge fuse are removably carried by a knob member which in turn is removably carried by a body member mounted on a panel or the like, wherein electrical connections are automatically established through the cartridge fuse and lamp when the knob member is removably secured to the body member, wherein the cartridge fuse and lamp may be readily and quickly replaced without danger of electrical shock, wherein the parts are sealed against moisture and dirt, and wherein the combined indicating fuse post and pilot light may be inexpensively and readily manufactured, installed and serviced.

Further objects of this invention reside in the details of construction of the combined indicating fuse post and pilot light and in the cooperative relationships between the component parts thereof.

Other objects and advantages of this invention will become apparent to those skilled in the art upon reference to the accompanying specification, claims and drawings, in which:

Fig. 1 is a perspective view of the combined indicating fuse post and pilot light of this invention;

Fig. 2 is a vertical sectional view through the combined indicating fuse post and pilot light taken substantially along the line 2—2 of Fig. 1;

Fig. 3 is a sectional view taken substantially along the line 3—3 of Fig. 2;

Fig. 4 is a sectional view taken substantially along the line 4—4 of Fig. 2;

Fig. 5 is a sectional view taken substantially along the line 5—5 of Fig. 2;

Fig. 6 is an enlarged sectional view taken substantially along the line 6—6 of Fig. 2;

Fig. 7 is a sectional view taken substantially along the line 7—7 of Fig. 2;

Figs. 8 and 9 are exploded perspective views illustrating the various parts forming the combined indicating fuse post and pilot light;

Fig. 10 is a wiring diagram of the combined indicating fuse post and pilot light.

The combined indicating fuse post and pilot light of this invention is generally designated at 10 and it includes a body member 11 constructed to be carried by a panel and a knob member 12 removably carried by the body member 11. The knob member 12 removably carries a lamp and a cartridge fuse and when the knob member is removably secured to the body member electrical connections are automatically established between terminals carried by the body member and the lamp and cartridge fuse carried by the knob member to connect the

2

cartridge fuse in series with the circuit being protected for protecting the same, to connect the cartridge fuse and lamp in series to brightly illuminate the lamp when electrical power is being supplied to the circuit being protected, and to connect the lamp in series with a resistor to dimly illuminate the lamp upon blowing of the cartridge fuse.

The body member 11 includes a substantially cylindrical hollow body portion 13 formed of electrical insulating material such as a thermosetting plastic of phenol formaldehyde or the like. The inner end of the body portion 13 is closed as indicated at 14 and the closure wall 14 is provided with a central recess 15. The outer open end of the body portion 13 is provided with a shouldered flange 16. The inner surface of the body portion 13 is provided with suitable guide grooves for receiving metallic terminals 18, 22 and 25, which terminals extend through suitable openings in the end closure wall 14 of the body member.

The first terminal 18 is provided with a spring clip 19 and with bent over ears 20, the terminal 18 being secured in the body portion 13 by a tongue 21. The clip 19, formed on the terminal 18, is located centrally of the body portion 12 adjacent the end closure wall 14. The second terminal 22 is provided with bent over ears 23 and is secured in place in the body portion 13 by a tongue 24. The third terminal 25 is provided with a clip 26 and is secured in place in the body portion 13 by a tongue 27. The clip 26 is located substantially midway between the ends of the body portion 13 and this clip 26 is in alignment with the clip 19 and is of larger diameter than the clip 19.

Secured to the open outer end 16 of the body portion 13 is a metallic ring 28. This metallic ring 28 is connected by a resistor 29 to the second terminal 22. The resistor 29 is formed from a strip of thermosetting material and is provided on one side with a resistance coating. The ends of the strip are coated with a silver paint or the like as indicated at 30 and 31, the end 30 being soldered into the terminal 22 behind the ears 23 and the end 31 being soldered to the contact ring 28. A resistor 32 is connected between the first and third terminals 18 and 25. Here also the resistor 32 may be formed of a strip of thermosetting material coated with a resistance material and provided at its ends 33 and 34 with a coating of silver paint or the like. The end 33 is soldered to the terminal 18 behind the ears 20 and the end 34 is soldered to the terminal 25 adjacent the clip 26. The resistance of the resistor 32 is many times greater than the resistance of the resistor 29. For example, the resistor 32 may have a resistance value of about one megohm while the resistor 29 may have a resistance value of about 75,000 ohms.

The body member 11 also includes a metallic mounting sleeve 36 which is exteriorly provided with screw threads 37, which is provided at its inner end with a hexagon configuration 38 and which is provided at its outer end with a shouldered flange 39 having internal screw threads 40. The body portion 13 of electrical insulating material is secured in the metallic mounting sleeve 36 with its shouldered end 16 engaging the shouldered end 39. The body member 11, thus formed, is inserted through a suitable hole in a panel with the shouldered flange 39 engaging the front of the panel. A nut 41 is then threaded onto the threads 37 for securing the body member to the panel. The hexagonal portion 38 is utilized for holding the body member stationary while the nut 41 is being tightened. Located between the shouldered flanges 16 and 39 of the body member 11 is an O-ring 42 which operates to seal the interior of the body member 11 when the knob member 12 is removably secured thereto.

The knob member 12 includes a pair of separable

parts 45 and 57. The part 45 is formed of electrical insulating material such as a thermoplastic material of nylon or the like. The part 45 which is generally of hollow cylindrical configuration is provided at one end with a pair of grooves 46 terminating in offset grooves 47 for forming a bayonet joint. A metallic contact sleeve 48 is secured in the part 45 and it is provided with grooved projections 49 which are received in the grooves 46. The grooved projections 49 terminate in slots 50 which are adjacent the grooves 47 in the part 45. Thus, the grooved projections 49 and the slots 50 cooperate with the grooves 46 and 47 in the part 45 to provide the female portion of a bayonet joint. The other end of the contact sleeve 48 is provided with a flange 51 which in turn is provided with a plurality of locking ears 52. The part 45 also has secured therein a metallic sleeve clip 54 provided with internally directed tongues 55.

The other part of the knob member 12 may be formed from a light transmitting electrical insulating material such as a thermoplastic material of polystyrene or the like. The part 57 is provided with an internal cavity 58 which in turn is provided with an internal groove 59. The part 57 is also externally provided with screw threads 60 to be received in the internal screw threads 40 of the body member 11. The locking ears 52 are resiliently forced outwardly by an annular coil spring 61. The parts 45 and 57 are removably secured together by the locking ears 52 being resiliently received in the internal annular groove 59. Thus, the parts 45 and 57 may be readily separated and secured together.

A lamp 62, such as a neon lamp, is removably mounted in the knob member 12. In this connection, the lamp 62 is provided with a sleeve contact 63 which in turn carries a pair of pins 64. The sleeve contact 63 is received in the contact sleeve 48 with the pins passing through the grooved projections 49 into the slots 50 for removably securing the lamp 62 in place. Thus, the lamp 62 may be readily replaced in the knob member 12 by merely removing the part 57. The sleeve contact 63 of the lamp makes electrical contact with the contact sleeve 48 either directly or through the pins 64. The lamp 62 is also provided with a central contact 65, the central contact 65 and the sleeve contact 63 forming a pair of contacts for the lamp 62.

The knob member 12 also removably carries a conventional cartridge fuse 67 having metallic end caps 68 and 69. The metallic end cap 68 of the cartridge fuse 67 is received in the sleeve clip 54, firm electrical contact being obtained by the interned tongues 55. The end cap 68 of the cartridge fuse 67 electrically contacts the central contact 65 of the lamp 62, the cartridge fuse and the lamp being arranged in end to end alignment. To insure good electrical contact between the end cap 68 of the cartridge fuse 67 and the central contact 65 of the lamp 62, a spring 71 is located in the central recess 15 of the body member 11 and is interposed between the end closure wall 14 and the end cap 69 of the cartridge fuse 67.

The first and second terminals 18 and 22 of the body member are electrically connected to opposite sides of an electrical power source. The third terminal 25 is electrically connected to the circuit being protected, the other end of this circuit being electrically associated with the power line leading to the second terminal 22. When the knob member 12 carrying the lamp 62 and the cartridge fuse 67, is inserted in the body member 11 by engaging the screw threads 40 and 60, the end cap 69 of the cartridge fuse 67 is received in the clip 19 of the terminal 18, the sleeve clip 54 is received in the clip 26 of the terminal 25 and the shoulder 51 on the contact sleeve 48 engages the contact ring 29. Thus, a circuit is completed from one side of the power source through the terminal 18, cartridge fuse 67, sleeve clip 54, and terminal 25 to the circuit being protected, the

cartridge fuse 67 protecting the circuit. Another circuit is completed from the same side of the power source through the terminal 18, cartridge fuse 67, central contact 65 and sleeve contact 63 of the lamp 62, contact sleeve 48, contact ring 28, resistor 29 and terminal 22 to the other side of the source of power. Since the resistance value of the resistor 29 is relatively low, the lamp 62, which is connected in series with the cartridge fuse 67, is brightly illuminated when electrical power is being supplied to the circuit being protected. This bright illumination of the lamp 62 passes through the light transmitting part 57 so that the lamp 62 here operates as a pilot lamp for indicating this condition. Another circuit is completed from the same side of the source of power through the terminal 18, resistor 32 and the clip 26 of the terminal 25, in shunt with the cartridge fuse 67, through the lamp 62, resistor 29 and terminal 22 to the other side of the power source since the cartridge fuse is in shunt with the resistor 32. This last mentioned circuit has no effect so long as the cartridge fuse is not blown. When, however, the cartridge fuse 67 blows the resistor 32 is connected in series with the lamp 62 and the resistor 29 to dimly illuminate the lamp 62. This dim illumination of the lamp 62 is indicated through the light transmitting part 57 to give an indication that the cartridge fuse 67 has been blown. A simplified wiring diagram is illustrated in Fig. 10, showing the above mentioned circuit.

To replace the cartridge fuse 67 after it has blown all that is necessary is to remove the knob member 12 and in so doing, the cartridge fuse 67 is extracted from the body member 11 when the knob member is removed. There are no exposed live parts so that the possibility of electrical shock is eliminated. The only exposed part, the contact ring 28, is connected through the resistor 29 so that the contact ring 28 is not hot. If the lamp 72 should become inoperative, it may be readily replaced by merely separating the part 57 from the remaining parts of the knob member 12, this of course, being done after the knob member 12 has been removed from the body member 11. When the knob member 12 is screwed into the body member 11 to complete the aforementioned circuits, the O-ring 42 is compressed to seal the inside of the fuse post against moisture and dirt.

While for purposes of illustration, one form of this invention has been disclosed, other forms thereof may become apparent to those skilled in the art upon reference to this disclosure and, therefore, this invention is to be limited only by the scope of the appended claims.

I claim as my invention:

1. A combined indicating fuse post and pilot light comprising, first and second terminals for electrical connection to opposite sides of an electrical power source, a third terminal for electrical connection to the circuit being protected; a cartridge fuse, a lamp having a pair of contacts, one of said lamp contacts being electrically connected to one end of the cartridge fuse, means for electrically connecting the other end of the cartridge fuse to said first terminal, means for electrically connecting said one end of the cartridge fuse to said third terminal to connect said cartridge fuse in series with the circuit being protected to protect the same, means including a resistor for electrically connecting the other lamp contact to said second terminal for connecting the cartridge fuse and lamp in series to brightly illuminate said lamp when electrical power is being supplied to the circuit being protected, and means including a resistor for electrically connecting said first and third terminals to dimly illuminate said lamp upon blowing of said cartridge fuse.

2. A combined indicating fuse post and pilot light comprising, a body member constructed to be carried by a panel and having first and second terminals for electrical connection to the opposite sides of an electrical power source and a third terminal for electrical connection to

the circuit being protected, a cartridge fuse, a lamp having a pair of contacts, a knob member removably carrying the cartridge fuse and the lamp with one of the lamp contacts electrically connected to one end of the cartridge fuse, means for removably securing the knob member to the body member, means operative upon removably securing the knob member to the body member for electrically connecting the other end of the cartridge fuse to said first terminal, means operative upon removably securing the knob member to the body member for electrically connecting said one end of the cartridge fuse to said third terminal to connect said cartridge fuse in series with the circuit being protected to protect the same, means operative upon removably securing the knob member to the body member and including a resistor for electrically connecting the other lamp contact to said second terminal for connecting the cartridge fuse and lamp in series to brightly illuminate said lamp when electrical power is being supplied to the circuit being protected, and means including a resistor for electrically connecting said first and third terminals to dimly illuminate said lamp upon blowing of said cartridge fuse.

3. A combined indicating fuse post and pilot light comprising, a body member constructed to be carried by a panel and having first and second terminals for electrical connection to the opposite sides of an electrical power source and a third terminal for electrical connection to the circuit being protected, a cartridge fuse, a lamp having a sleeve contact and a central contact, a knob member removably carrying the cartridge fuse and the lamp in end to end alignment with one end of the cartridge fuse electrically contacting the central contact of the lamp, means for removably securing the knob member to the body member, means operative upon removably securing the knob member to the body member for electrically connecting the other end of the cartridge fuse to said first terminal, means operative upon removably securing the knob member to the body member for electrically connecting said one end of the cartridge fuse to said third terminal to connect said cartridge fuse in series with the circuit being protected to protect the same, means operative upon removably securing the knob member to the body member and including a resistor for electrically connecting the sleeve contact of the lamp to said second terminal for connecting the cartridge fuse and lamp in series to brightly illuminate said lamp when electrical power is being supplied to the circuit being protected, and means including a resistor for electrically connecting said first and third terminals to dimly illuminate said lamp upon blowing of said cartridge fuse.

4. A combined indicating fuse post and pilot light comprising, a body member constructed to be carried by a panel and having first and second terminals for electrical connection to the opposite sides of an electrical power source and a third terminal for electrical connection to the circuit being protected, a cartridge fuse, a lamp having a sleeve contact and a central contact, a knob member removably carrying the cartridge fuse and the lamp in end to end alignment with one end of the cartridge fuse electrically contacting the central contact of the lamp, means for removably securing the knob member to the body member, means operative upon removably securing the knob member to the body member for electrically connecting the other end of the cartridge fuse to said first terminal, means operative upon removably securing the knob member to the body member for electrically connecting said one end of the cartridge fuse to said third terminal to connect said cartridge fuse in series with the circuit being protected to protect the same, means operative upon removably securing the knob member to the body member and including a resistor for electrically connecting the sleeve contact of the lamp to said second terminal for connecting the cartridge fuse and lamp in series to brightly illuminate said lamp when electrical power is being supplied to the circuit being

protected, and means including a resistor for electrically connecting said first and third terminals to dimly illuminate said lamp upon blowing of said cartridge fuse, and a spring carried by the body member for engaging said other end of the cartridge fuse when the knob member is removably secured to the body member for forcing said one end of the cartridge fuse against the central contact of the lamp.

5. A combined indicating fuse post and pilot light comprising, a substantially cylindrical hollow body member formed of electrical insulating material and closed at its inner end and open at its outer end, first and second electrical terminals extending through the closed inner end of the body member for electrical connection to opposite sides of an electrical power source, a third terminal extending through the closed inner end of the body member for electrical connection to the circuit being protected, a contact ring carried by the body member at the open outer end thereof, means including a resistor for electrically connecting said second terminal to the contact ring, a clip on said third electrical terminal intermediate the ends of the body member, a clip on said first electrical terminal adjacent the closed inner end of the body member, a resistor electrically connected between said first and third terminals, a cartridge fuse, a lamp having a sleeve contact and a central contact, a substantially cylindrical hollow knob member formed of electrical insulating material and having a contact sleeve and a sleeve clip, said lamp being removably secured in the contact sleeve with its sleeve contact electrically contacting the contact sleeve, one end of said cartridge fuse being removably secured in said sleeve clip in electrical contact therewith and with the central contact of said lamp, the other end of said cartridge fuse projecting from the knob member, and means for removably securing the knob member to the body member with said other end of the cartridge fuse electrically contacting the clip of the first terminal, with said sleeve clip electrically contacting the clip on said third terminal and with said contact sleeve electrically contacting said contact ring to connect said cartridge fuse in series with the circuit being protected to protect the same, to connect said cartridge fuse and lamp in series to brightly illuminate said lamp when electrical power is being supplied to the circuit being protected, and to connect said first mentioned resistor in series with said lamp to dimly illuminate said lamp upon blowing of said cartridge fuse.

6. A combined indicating fuse post and pilot light comprising, a substantially cylindrical hollow body member formed of electrical insulating material and closed at its inner end and open at its outer end, first and second electrical terminals extending through the closed inner end of the body member for electrical connection to opposite sides of an electrical power source, a third terminal extending through the closed inner end of the body member for electrical connection to the circuit being protected, a contact ring carried by the body member at the open outer end thereof, means including a resistor for electrically connecting said second terminal to the contact ring, a clip on said third electrical terminal intermediate the ends of the body member, a clip on said first electrical terminal adjacent the closed inner end of the body member, a resistor electrically connected between said first and third terminals, a cartridge fuse, a lamp having a sleeve contact and a central contact, a substantially cylindrical hollow knob member formed of electrical insulating material and having a contact sleeve and a sleeve clip, said lamp being removably secured in the contact sleeve with its sleeve contact electrically contacting the contact sleeve, one end of said cartridge fuse being removably secured in said sleeve clip in electrical contact therewith and with the central contact of said lamp, the other end of said cartridge fuse projecting from the knob member, and means for removably securing the knob member to the body mem-

ber with said other end of the cartridge fuse electrically contacting the clip of the first terminal, with said sleeve clip electrically contacting the clip on said third terminal and with said contact sleeve electrically contacting said contact ring to connect said cartridge fuse in series with the circuit being protected to protect the same, to connect said cartridge fuse and lamp in series to brightly illuminate said lamp when electrical power is being supplied to the circuit being protected, and to connect said first mentioned resistor in series with said lamp to dimly illuminate said lamp upon blowing of said cartridge fuse, and a spring interposed between the closed inner end of the body member and said other end of the cartridge fuse when the knob member is removably secured to the body member for forcing said one end of the cartridge fuse against the central contact of the lamp.

7. A combined indicating fuse post and pilot light comprising, a substantially cylindrical hollow body member formed of electrical insulating material and closed at its inner end and open at its outer end, first and second electrical terminals extending through the closed inner end of the body member for electrical connection to opposite sides of an electrical power source, a third terminal extending through the closed inner end of the body member for electrical connection to the circuit being protected, a contact ring carried by the body member at the open outer end thereof, means including a resistor for electrically connecting said second terminal to the contact ring, a clip on said third electrical terminal intermediate the ends of the body member, a clip on said first electrical terminal adjacent the closed inner end of the body member, a resistor electrically connected between said first and third terminals, a cartridge fuse, a lamp having a sleeve contact and a central contact, a hollow knob member formed of insulating material and including two separable parts, one of said parts having a contact sleeve and a sleeve clip, said lamp being removably secured in the contact sleeve with its sleeve contact electrically contacting the contact sleeve and being enclosed by the other part of the knob member, one end of said cartridge fuse being removably secured in said sleeve clip in electrical contact therewith and with the central contact of said lamp, the other end of said cartridge fuse projecting from the knob member, and means for removably securing the knob member to the body member with said other end of the cartridge fuse electrically contacting the clip of the first terminal, with said sleeve clip electrically contacting the clip on said third terminal and with said contact sleeve electrically contacting said contact ring to connect said cartridge fuse in series with the circuit being protected to protect the same, to connect said cartridge fuse and lamp in series to brightly illuminate said lamp when electrical power is being supplied to the circuit being protected, and to connect said first mentioned resistor in series with said lamp to dimly illuminate said lamp upon blowing of said cartridge fuse.

8. In a combined indicating fuse post and pilot light including a cartridge fuse for protecting an electric circuit and a lamp having a pair of contacts and which is brightly illuminated when electrical power is being supplied to the circuit being protected and which is dimly illuminated when the cartridge fuse is blown, the improvement consisting of, first and second terminals for electrical connection to opposite sides of an electrical power source, a third terminal for electrical connection to the circuit being protected, one of said lamp contacts being electrically connected to one end of the cartridge fuse, means for electrically connecting the other end of the cartridge fuse to said first terminal, means for electrically connecting said one end of the cartridge fuse to said third terminal to connect said cartridge fuse in series with the circuit being protected to protect the same, means including a resistor for electrically connecting the other lamp contact to said second terminal for connect-

ing the cartridge fuse and lamp in series to brightly illuminate said lamp when electrical power is being supplied to the circuit being protected, and means including a resistor for electrically connecting said first and third terminals to dimly illuminate said lamp upon blowing of said cartridge fuse.

9. In a combined indicating fuse post and pilot light including a cartridge fuse for protecting an electric circuit, a lamp having a pair of contacts and which is brightly illuminated when electrical power is being supplied to the circuit being protected and which is dimly illuminated when the cartridge fuse is blown, a body member constructed to be carried by a panel and a knob member removably carried by the body member, the improvement consisting of, first and second terminals carried by the body member for electrical connection to the opposite sides of an electrical power source, a third terminal carried by the body member for electrical connection to the circuit being protected, said knob member removably carrying the cartridge fuse and the lamp with one of the lamp contacts electrically connected to one end of the cartridge fuse, means operative upon removably securing the knob member to the body member for electrically connecting the other end of the cartridge fuse to said first terminal, means operative upon removably securing the knob member to the body member for electrically connecting said one end of the cartridge fuse to said third terminal to connect said cartridge fuse in series with the circuit being protected to protect the same, means operative upon removably securing the knob member to the body member and including a resistor for electrically connecting the other lamp contact to said second terminal for connecting the cartridge fuse and lamp in series to brightly illuminate said lamp when electrical power is being supplied to the circuit being protected, and means including a resistor for electrically connecting said first and third terminals to dimly illuminate said lamp upon blowing of said cartridge fuse.

10. In a combined indicating fuse post and pilot light including a cartridge fuse for protecting an electric circuit, a lamp having a sleeve contact and a central contact and which is brightly illuminated when electrical power is being supplied to the circuit being protected and which is dimly illuminated when the cartridge fuse is blown, a body member constructed to be carried by a panel and a knob member removably carried by the body member, the improvement consisting of, first and second terminals carried by the body member for electrical connection to the opposite sides of an electrical power source, a third terminal carried by the body member for electrical connection to the circuit being protected, said knob member removably carrying the cartridge fuse and the lamp in end to end alignment with one end of the cartridge fuse electrically contacting the central contact of the lamp, means operative upon removably securing the knob member to the body member for electrically connecting the other end of the cartridge fuse to said first terminal, means operative upon removably securing the knob member to the body member for electrically connecting said one end of the cartridge fuse to said third terminal to connect said cartridge fuse in series with the circuit being protected to protect the same, means operative upon removably securing the knob member to the body member and including a resistor for electrically connecting the sleeve contact of the lamp to said second terminal for connecting the cartridge fuse and lamp in series to brightly illuminate said lamp when electrical power is being supplied to the circuit being protected, and means including a resistor for electrically connecting said first and third terminals to dimly illuminate said lamp upon blowing of said cartridge fuse.

11. In a combined indicating fuse post and pilot light including a cartridge fuse for protecting an electric circuit, a lamp having a sleeve contact and a central contact and which is brightly illuminated when electrical power

is being supplied to the circuit being protected and which is dimly illuminated when the cartridge fuse is blown, a body member constructed to be carried by a panel and a knob member removably carried by the body member, the improvement consisting of, first and second terminals carried by the body member for electrical connection to the opposite sides of an electrical power source, a third terminal carried by the body member for electrical connection to the circuit being protected, said knob member removably carrying the cartridge fuse and the lamp in end to end alignment with one end of the cartridge fuse electrically contacting the central contact of the lamp, means operative upon removably securing the knob member to the body member for electrically connecting the other end of the cartridge fuse to said first terminal, means operative upon removably securing the knob member to the body member for electrically connecting said one end of the cartridge fuse to said third terminal to connect said cartridge fuse in series with the circuit being protected to protect the same, means operative upon removably securing the knob member to the body member and including a resistor for electrically connecting the sleeve contact of the lamp to said second terminal for connecting the cartridge fuse and lamp in series to brightly illuminate said lamp when electrical power is being supplied to the circuit being protected, and means including a resistor for electrically connecting said first and third terminals to dimly illuminate said lamp upon blowing of said cartridge fuse, and a spring carried by the body member for engaging said other end of the cartridge fuse when the knob member is removably secured to the body member for forcing said one end of the cartridge fuse against the central contact of the lamp.

12. In a combined indicating fuse post and pilot light including a cartridge fuse for protecting an electric circuit, a lamp having a sleeve contact and a central contact and which is brightly illuminated when electrical power is being supplied to the circuit being protected and which is dimly illuminated when the cartridge fuse is blown, a substantially cylindrical hollow body member formed of electrical insulating material and closed at its inner end and open at its outer end, and a substantially cylindrical hollow knob member formed of electrical insulating material and removably carried by the body member, the improvement consisting of, first and second electrical terminals extending through the closed inner end of the body member for electrical connection to opposite sides of an electrical power source, a third terminal extending through the closed inner end of the body member for electrical connection to the circuit being protected, a contact ring carried by the body member at the open outer end thereof, means including a resistor for electrically connecting said second terminal to the contact ring, a clip on said third electrical terminal intermediate the ends of the body member, a clip on said first electrical terminal adjacent the closed inner end of the body member, a resistor electrically connected between said first and third terminals, a contact sleeve and a sleeve clip carried by the knob member, said lamp being removably secured in the contact sleeve with its sleeve contact electrically contacting the contact sleeve, one end of said cartridge fuse being removably secured in said sleeve clip in electrical contact therewith and with the central contact of said lamp, the other end of said cartridge fuse projecting from the knob member, and means for removably securing the knob member to the body member with said other end of the cartridge fuse electrically contacting the clip of the first terminal, with said sleeve clip electrically contacting the clip on said third terminal and with said contact sleeve electrically contacting said contact ring to connect said cartridge fuse in series with the circuit being protected to protect the same, to connect said cartridge fuse and lamp in series to brightly illuminate said lamp when electrical power is being supplied to the circuit being protected, and to connect said first mentioned resistor in series with said lamp to dimly illuminate said lamp upon blowing of said cartridge fuse, and a spring interposed between the closed inner end of the body member and said other end of the cartridge fuse when the knob member is removably secured to the body member for forcing said one end of the cartridge fuse against the central contact of the lamp.

tioned resistor in series with said lamp to dimly illuminate said lamp upon blowing of said cartridge fuse.

13. In a combined indicating fuse post and pilot light including a cartridge fuse for protecting an electric circuit, a lamp having a sleeve contact and a central contact and which is brightly illuminated when electrical power is being supplied to the circuit being protected and which is dimly illuminated when the cartridge fuse is blown, a substantially cylindrical hollow body member formed of electrical insulating material and closed at its inner end and open at its outer end, and a substantially cylindrical hollow knob member formed of electrical insulating material and removably carried by the body member, the improvement consisting of, first and second electrical terminals extending through the closed inner end of the body member for electrical connection to opposite sides of an electrical power source, a third terminal extending through the closed inner end of the body member for electrical connection to the circuit being protected, a contact ring carried by the body member at the open outer end thereof, means including a resistor for electrically connecting said second terminal to the contact ring, a clip on said third electrical terminal intermediate the ends of the body member, a clip on said first electrical terminal adjacent the closed inner end of the body member, a resistor electrically connected between said first and third terminals, a contact sleeve and a sleeve clip carried by the knob member, said lamp being removably secured in the contact sleeve with its sleeve contact electrically contacting the contact sleeve, one end of said cartridge fuse being removably secured in said sleeve clip in electrical contact therewith and with the central contact of said lamp, the other end of said cartridge fuse projecting from the knob member, and means for removably securing the knob member to the body member with said other end of the cartridge fuse electrically contacting the clip of the first terminal, with said sleeve clip electrically contacting the clip on said third terminal and with said contact sleeve electrically contacting said contact ring to connect said cartridge fuse in series with the circuit being protected to protect the same, to connect said cartridge fuse and lamp in series to brightly illuminate said lamp when electrical power is being supplied to the circuit being protected, and to connect said first mentioned resistor in series with said lamp to dimly illuminate said lamp upon blowing of said cartridge fuse, and a spring interposed between the closed inner end of the body member and said other end of the cartridge fuse when the knob member is removably secured to the body member for forcing said one end of the cartridge fuse against the central contact of the lamp.

14. In a combined indicating fuse post and pilot light including a cartridge fuse for protecting an electric circuit, a lamp having a sleeve contact and a central contact and which is brightly illuminated when electrical power is being supplied to the circuit being protected and which is dimly illuminated when the cartridge fuse is blown, a substantially cylindrical hollow body member formed of electrical insulating material and closed at its inner end and open at its outer end, and a substantially cylindrical hollow knob member formed of electrical insulating material and removably carried by the body member, the improvement consisting of, first and second electrical terminals extending through the closed inner end of the body member for electrical connection to opposite sides of an electrical power source, a third terminal extending through the closed inner end of the body member for electrical connection to the circuit being protected, a contact ring carried by the body member at the open outer end thereof, means including a resistor for electrically connecting said second terminal to the contact ring, a clip on said third electrical terminal intermediate the ends of the body member, a clip on said first electrical terminal adjacent the closed inner end of the body member, a resistor electrically connected between said first and third terminals, a contact sleeve and a sleeve clip carried by the knob member, said lamp being removably secured in the contact sleeve with its sleeve contact electrically contacting the contact sleeve, one end of said cartridge fuse being removably secured in said sleeve clip in electrical contact therewith and with the central contact of said lamp, the other end of said cartridge fuse projecting from the knob member, and means for removably securing the knob member to the body member with said other end of the cartridge fuse electrically contacting the clip of the first terminal, with said sleeve clip electrically contacting the clip on said third terminal and with said contact sleeve electrically contacting said contact ring to connect said cartridge fuse in series with the circuit being protected to protect the same, to connect said cartridge fuse and lamp in series to brightly illuminate said lamp when electrical power is being supplied to the circuit being protected, and to connect said first mentioned resistor in series with said lamp to dimly illuminate said lamp upon blowing of said cartridge fuse, and a spring interposed between the closed inner end of the body member and said other end of the cartridge fuse when the knob member is removably secured to the body member for forcing said one end of the cartridge fuse against the central contact of the lamp.

11

of the body member, a resistor electrically connected between said first and third terminals, said hollow knob member including two separable parts, one of said parts having a contact sleeve and a sleeve clip, said lamp being removably secured in the contact sleeve with its sleeve contact electrically contacting the contact sleeve and being enclosed by the other part of the knob member, one end of said cartridge fuse being removably secured in said sleeve clip in electrical contact therewith and with the central contact of said lamp, the other end of said cartridge fuse projecting from the knob member, and means for removably securing the knob member to the body member with said other end of the cartridge fuse electrically contacting the clip of the first terminal, with said sleeve clip electrically contacting the clip on 15 said third terminal and with said contact sleeve electrically contacting said contact ring to connect said car-

tridge fuse in series with the circuit being protected to protect the same, to connect said cartridge fuse and lamp in series to brightly illuminate said lamp when electrical power is being supplied to the circuit being protected, and to connect said first mentioned resistor in series with said lamp to dimly illuminate said lamp upon blowing of said cartridge fuse.
